UNITED STATES PATENT OFFICE.

RICHARD W. GAFFNEY, OF YONKERS, NEW YORK.

HYDRAULIC JACK.

1,244,317.

Specification of Letters Patent. Patented Oct. 23, 1917.

Application filed September 18, 1916. Serial No. 119,824.

To all whom it may concern:

Be it known that I, RICHARD W. GAFFNEY, a citizen of the United States, and a resident of Yonkers, in the county of Westchester and State of New York, have invented 5 a new and Improved Hydraulic Jack, of which the following is a full, clear, and exact description.

The invention relates to hydraulic jacks 10 such as shown and described in the Letters Patent of the United States, No. 1,046,207, granted to Frank Lynt on December 3, 1912.

The object of the present invention is to provide a new and improved hydraulic jack 15 of the type referred to, and which is simple and durable in construction, cheap to manufacture and readily carried about and placed in position for use on heavy trucks, automobiles and the like.

20 In order to produce the desired result, use is made of a casing provided externally with spaced lugs, a cylinder within the casing and containing a piston having its piston rod extending through the cap which closes the 25 casing and the cylinder, and a pump having a barrel attached to said lugs and spaced from the said casing to form a handle for the hydraulic jack, the said pump having a valved connection with the said cylinder by 30 way of one of the said lugs.

A practical embodiment of the invention is represented in the accompanying drawings forming a part of this specification, in which similar characters of reference indicate corresponding parts in all the views.

Figure 1 is a sectional side elevation of the hydraulic jack on the line 1—1 of Fig. 2;

Fig. 2 is a sectional plan view of the same on the line 2—2 of Fig. 1; and

40 Fig. 3 is a sectional side elevation of the return valve, the section being on the line 3—3 of Fig. 2.

The casing 10 of the hydraulic jack is provided with a base 11 in which screws 45 the lower end of a cylinder 12 at the reduced recess 13 of the said base so that the cylinder 12 forms with the casing 10 an annular reservoir 14 for containing oil or other liquid used in operating the hydraulic 50 jack. The cylinder 12 may be made of plain tubing and by being screwed in the base 11 of the casing 10 the two parts can be readily assembled and cheaply manufactured. The upper ends of the casing 10 and

the cylinder 12 are closed by a cap 15 provided with a depending rim 16 having a beveled edge 17 fitting onto a correspondingly beveled edge 18 on the upper end of the casing 10 thus closing the upper end thereof without danger of leakage. The 60 cap 15 is further provided with a depending annular flange 19 concentric with the rim 16 and screwing on the upper end 20 of the cylinder 12 thus holding the cap in position and closing both the casing 10 and 65 the cylinder 12. The flange 19 is provided with an opening 21 extending above the top of the cylinder 12 to provide communication between the reservoir 14 and the upper end of the cylinder 12 to permit a ready 70 flow of the liquid, as hereinafter more fully explained.

Within the cylinder 12 is mounted to reciprocate a piston 25 provided with a piston rod 26 extending upwardly through a stuffing box 27 held on the cap 15. The outer end of the piston rod 26 is provided with the usual head 28 adapted to engage an axle or other part to be raised or lowered. The piston 25 is provided with a relief valve 29 normally closed and adapted to move into open position on the top of the valve coming into contact with the under side of the cap 15 at the time the piston 25 moves into uppermost position.

85 Lugs 30 and 31 are formed integrally on the side of the casing 10 and the said lugs are located one above the other, and to the said lugs are secured the lower and upper ends 32 and 33 of a barrel 34 of a pump for pumping the liquid into the cylinder 12. By the arrangement described the barrel 34 intermediate its ends 32 and 33 is spaced 90 from the casing 10 and thus forms a handle for conveniently carrying the hydraulic jack about from one place to another. Within the barrel 34 is mounted to reciprocate a plunger 35 extending at its upper end through a stuffing box 36 held on the upper end 33 of the barrel 34. The upper end of the plunger 35 is connected by a link 37 with a hand lever 38 fulcrumed at 39 on the top of the cap 15.

100 The lower end of the barrel 34 of the pump has a valved connection 40 with the lower end of the cylinder 12, and a valved connection 41 connects the lower end of the reservoir 14 with the lower end of the said

barrel 34. The valved connections 40 and 41 are so arranged that when the plunger 35 is raised then the oil or other liquid contained in the reservoir 14 is drawn by way of the valved connection 41 into the pump barrel 34. When the plunger 35 is moved downward then the valved connection 41 closes and the valved connection 40 is opened so that the liquid contained in the barrel 34 is forced out of the same into the lower end of the cylinder 12 to raise the piston 25 therein. Thus on alternately raising and lowering the pump plunger 35, the piston 25 in the cylinder 12 is gradually raised by the incoming liquid whereby the axle or other part resting on the head 28 is lifted. When it is desired to lower the part then the lower end of the cylinder 12 is connected with the lower end of the reservoir 14 to allow the liquid to flow from the cylinder 12 back into the reservoir 14, and for this purpose use is made of a needle valve 50 adapted to connect the lower end of the cylinder 12 with the reservoir 14. It is understood that when the needle valve 50 is open then the weight of the part on the top of the head 28 forces the piston 25 downward in the cylinder 12 and this movement is gradual owing to the flow of the liquid from the cylinder 12 into the reservoir 14 by way of the open needle valve 50. The outer end of the needle valve 50 is provided with a suitable handle 51 for conveniently turning the needle valve into open or closed position.

By reference to the drawings it will be noticed that the valved connections 40 and 41 for the cylinder 12 and the reservoir 14 are by way of the lower lug 30 and the lower end 32 of the pump barrel 34, and the needle valve 50 is likewise located in the said lug 30 and the barrel end 32.

When it is desired to lift the parts lower down than the head 28 use is made of a sleeve 60 mounted to slide up and down on the outside of the casing 10. The sleeve 60 is provided at one side with a cut-out portion 61 straddling the lugs 30 and 31 thus guiding the sleeve 60 in its up or down movement. The sleeve 60 is provided with a top 62 resting on the lifting head 28. The lower end of the sleeve 60 is provided with a lifting foot 63 extending outwardly and adapted to engage the part to be lifted. It is understood that when the piston 25 is moved upward on operating the pump as previously explained then the sleeve 60 is lifted and with it the part to be raised and resting on the foot 63.

Having thus described my invention, I claim as new and desire to secure by Letters Patent:

1. In a hydraulic jack, a casing provided at the side with spaced lugs, a cylinder with- 65 in the said casing and provided with a pis-

ton, the cylinder and casing being spaced apart to form a reservoir between them, and a pump having a barrel attached to the said lugs and spaced from the side of the casing to form a handle.

2. In a hydraulic jack, a casing provided at the side with spaced lugs, a cylinder within the said casing and provided with a piston, the cylinder and casing being spaced apart to form a reservoir between them, and a pump having a barrel attached to the said lugs and spaced from the side of the casing to form a handle, the said barrel being in communication with the said casing cylinder by way of one of the said lugs.

3. In a hydraulic jack, a casing provided at the side with spaced lugs, a cylinder within the said casing and provided with a piston, the cylinder and casing being spaced apart to form a reservoir between them, a pump having a barrel attached to the said lugs and spaced from the side of the casing to form a handle, and a valved connection between the lower end of the said pump barrel and the lower ends of the said cylinder 90 and reservoir.

4. In a hydraulic jack, a casing having a base and being open at the top, the said base having a reduced recess, a cylinder having its lower end attached to the wall of the 95 said recess, and a cap screwing on the upper end of the said cylinder and fitting onto the upper end of the said cylinder and fitting onto the upper end of the said casing.

5. In a hydraulic jack, a casing having a 100 base provided with a recess, the upper end of the casing being beveled, a cylinder screwing into the recessed portion of the base and being spaced at the side from the side of the casing to form with the latter an annular reservoir, a cap having the lower edge of its rim beveled and fitting onto the beveled upper end of the said casing, the cap being provided with a threaded flange screwing on the upper end of the said cylinder, and a piston 110 mounted to reciprocate in the said cylinder and having its piston rod extending through the said cap.

6. In a hydraulic jack, a casing having a base provided with a recess, the upper end 115 of the casing being beveled, a cylinder screwing into the recessed portion of the base and being spaced at the side from the side of the casing to form with the latter an annular reservoir, a cap having the lower 120 edge of its rim beveled and fitting onto the beveled upper end of the said casing, the cap being provided with a threaded flange screwing on the upper end of the said cylinder, a piston mounted to reciprocate in the 125 said cylinder and having its piston rod extending through the said cap, a pump having its barrel secured at the ends to the side of the casing, the barrel being spaced from the casing to form a handle for the jack, and 130

a valved connection connecting the lower end of the pump barrel with the lower ends of the said cylinder and the said reservoir.

7. In a hydraulic jack, a casing, a cylinder within the casing and forming with the latter a reservoir, a cap closing the upper ends of the said casing and cylinder, a piston mounted to reciprocate in the said cylinder and having a piston rod extending 10 through the said cap, a lifting head on the upper end of the said piston rod, spaced lugs on the outside of the said casing, a pump attached to the said lugs and spaced from the casing to form a handle, and a valved connection 15 between the said pump and the said cylinder and reservoir, the said valved connection being by way of one of the said lugs.

8. In a hydraulic jack, a casing, a cylinder within the casing and forming with the latter a reservoir, a cap closing the upper ends 20

of the said casing and cylinder, a piston mounted to reciprocate in the said cylinder and having a piston rod extending through the said cap, a lifting head on the upper end of the said piston rod, lugs on the outside of 25 the said casing, a pump attached to the said lugs, a valved connection between the said pump and the said cylinder and reservoir, the said valved connection being by way of one of the said lugs, and a sleeve slidably exteriorly up and down on the said casing and being guided by the said lugs, the said sleeve having a top resting on the said lifting head and the said sleeve being provided at its lower end with a lifting foot. 30
